US00D564095S

(12) **United States Design Patent** (10) **Patent No.:** **US D564,095 S**
Blain (45) **Date of Patent:** **** Mar. 11, 2008**

(54) **INTERBODY FUSION DEVICE**

(75) Inventor: **Jason Blain**, Encinitas, CA (US)

(73) Assignee: **Spinal Elements, Inc.**, Carlsbad, CA (US)

(**) Term: **14 Years**

(21) Appl. No.: **29/273,496**

(22) Filed: **Apr. 3, 2006**

Related U.S. Application Data

(62) Division of application No. 29/242,012, filed on Nov. 4, 2005, now Pat. No. Des. 533,277.

(51) **LOC (8) Cl.** **24-03**

(52) **U.S. Cl.** **D24/155**

(58) **Field of Classification Search** **D24/155; 606/61, 72, 74; 623/17.16, 17.17, 11.11**

See application file for complete search history.

CLAIM

The ornamental design for an interbody fusion device, as shown and described.

DESCRIPTION

FIG. 1 is a rear perspective view of an interbody fusion device showing my new design;

FIG. 2 is a right side elevation thereof;

FIG. 3 is a left side elevation thereof;

FIG. 4 is a rear elevation thereof;

FIG. 5 is a front elevation thereof;

FIG. 6 is a top plan view thereof; and,

FIG. 7 is a bottom plan view thereof.

The broken lines shown in the drawings are included for purposes of illustration and form no part of the claimed design.
